RETARD DEVICE FOR SPRINKLER SYSTEMS

Application filed February 5, 1930. Serial No. 425,936.

The present invention relates to an improved flow retarding device for use in automatic sprinkler systems or the like.

More specifically the invention comprises a compact device of simple construction and of relatively small dimensions adapted positively to prevent the flow of water to the alarm until after a desired interval of time and thereafter to permit a direct and relatively large flow of water thereto, whereby water hammer or the like is ineffective to actuate the alarm.

For an understanding of the invention reference may be had to the accompanying drawing in which is illustrated partly in section a retarding device embodying the invention.

Referring to the drawing, a cylindrical casting 1 is provided with a horizontal partition 2 near the lower part thereof which divides the interior of the casting into an inlet chamber 3 below the partition and an accumulation chamber 4 above the partition. Chamber 3 is closed on its lower side by a diaphragm 5, and chamber 4 on its upper side is closed by a diaphragm 6. A lower casting 7 provided with a threaded opening 8 for connection to a drain pipe is fastened to the casting 1 by means of bolts 9, which bolts pass through holes in diaphragm 5 and in suitable gaskets between the diaphragm and casing sections. An upper casting 10 for housing the contacts of an electrical alarm device is similarly bolted to the casting 1 so as to hold diaphragm 6 therebetween. Casing section 10 is closed by a top section 11 screw threadedly mounted thereon. A right angle partition 12 connected between partition 2 and a wall of casing 1 forms an outlet chamber 13 about a threaded opening 14 into which the pipe leading to the water alarm is adapted to be connected. A similar threaded opening 15 is provided in the wall of casing 1 leading into chamber 3 for connection of the pipe leading from the usual alarm valve. Casing section 7 above the drain connection 8 encloses a chamber 16 opening laterally into an annular groove 17 within which is a compression spring 18 normally tending to hold diaphragm 5 away from the closed upper end of

chamber 16. Diaphragm 5 is provided with a central aperture 19 for the drainage of water from the device when the diaphragm is raised, which aperture is closed when the pressure in chamber 3 is sufficient to depress the diaphragm against the closed top of chamber 16 in opposition to the tension of spring 18.

Threaded into partition 2 is a short member 20 provided with a passage 21 therethrough for the admission of water into the accumulation chamber 4. The passage 21 is of relatively small bore and is protected from clogging as with dirt by a screen 22 soldered to the lower side of a nut integral with member 20. Drainage from chamber 4 independent of the passage 21 is permitted through a short pipe 23 threaded into partition 2. A nut 24 integral with pipe 23 has fastened thereto a framework 25 of wires enclosing the lower opening of the pipe 23. A disk 26 of sufficient area to cover the open end of the pipe 23, carried within the framework 25, normally permits drainage of chamber 4 through pipe 23, but is raised against the end of the pipe to cut off the passage of water therethrough upon an increase of pressure in chamber 3 above that in chamber 4.

Slidably mounted in partition 12 is a rod 27 linked at its upper end to a lever 28 pivoted upon an upright 29 mounted on partition 2. The lower end of rod 27 has pinned thereto a tube 30 from which is suspended a member 31 carrying a disk valve 32 for a port 33 between chambers 3 and 13. A cut out portion of member 31 through which passes a pin 34 fastened in the walls of tube 30 permits a slight movement of disk 32 relative to rod 27 whereby the disk is raised to close port 33 when rod 27 is in raised position and when the pressure in chamber 3 exceeds that in chamber 13. When the pressure in chamber 3 is insufficient to raise disk 32, the disk falls by gravity to the position shown to permit drainage from the alarm. Positive opening of port 33 is effected when rod 27 is in its lowermost position, at which time relative upward movement of disk 32 is ineffective to close port 33.

The other end of lever 28 is linked to a

member 35 rigidly mounted, as by means of screw 36, on diaphragm 6. Diaphragm 6 is normally depressed by an insulating piston 37 carried between guides in casing section 10 and forced downwardly against the upper side of the diaphragm by a spring 38. Upon increase in pressure in chamber 4, due to the filling thereof with water through port 21, diaphragm 6 is raised against the tension of spring 38 to tip lever 28 and thereby to depress rod 27 to open port 33. The upward movement of insulating piston 37, caused by upward pressure upon diaphragm 6, serves to energize an electric alarm device (not shown) by closure of electric contacts 39 and 40 suitably mounted upon casting section 10 and connected by means of wires 41 and 42 with the circuit of the electric alarm.

From the above description, it will be apparent that an increase in pressure in chamber 3, occasioned by a steady inflow of water through the inlet 15, operates to close all outlets from this chamber with the exception of the small port 21 leading into the accumulation chamber 4. As the flow continues, chamber 4 will gradually be filled sufficiently to raise diaphragm 6 and thereby to open wide port 33 to permit water to flow directly from chamber 3 to the water alarm and to close contacts 39 and 40 to sound the electric alarm. Upon cessation of water inflow, the consequent decrease in pressure in chamber 3 permits disk 26 to fall against wires 25 opening the drain passage for chamber 4. The decrease in pressure in chamber 3 likewise permits spring 18 to lift diaphragm 5 and thereby to drain the device through port 19, chambers 17 and 16 and drain outlet 8. As the accumulation chamber becomes drained and the pressure therein diminishes, spring 38 moves diaphragm 6 downward to lift rod 27 and to open the circuit of the electric alarm. Disc 32 also drops allowing drainage of the water motor line.

The retarding device above described, due to the provision of the restricted opening into the accumulation chamber combined with the relatively large drainage area therefrom, and due to the provision of the relatively large outlet for the water to the alarm device leading directly from the inlet chamber, can be made of relatively smaller dimensions than can devices heretofore in use, with consequent saving in cost of materials and in space occupied. Furthermore, the simple construction and operation of the various valves are such that the device is positive in action and substantially fool-proof. An increase in pressure in the inlet chamber, due for example to water hammer, that is not of sufficient duration to cause the filling of the accumulation chamber, will be ineffective to cause actuation of either the electric or the water alarm. Accumulation of water in any

part of the device is prevented by the provision of a complete drainage system.

The following is claimed:

1. A retard device for automatic sprinkler systems comprising a casing, a partition therein dividing the space within said casing into a relatively small inlet chamber and a relatively large accumulation chamber, said partition being provided with a permanently open passage therethrough of small bore and with a drainage passage therethrough of relatively large bore means adapted to close said drainage passage only when the pressure in the inlet chamber exceeds that in the accumulation chamber, pressure responsive means adapted to form one wall of the accumulation chamber, means including an outlet passage from said inlet chamber for permitting water to flow from said inlet chamber to actuate a water alarm of the system, a valve for controlling said outlet passage and means for controlling said valve by said pressure responsive means.

2. A retard device according to claim 1 including means whereby said valve partially opens by gravity when water is not being supplied to the inlet chamber.

3. A retard device according to claim 1 including pressure responsive means forming one wall of said inlet chamber and provided with an aperture therethrough for draining said inlet chamber when said responsive means is in one position, and a surface carried by said casing adapted to close said aperture to prevent drainage therethrough when said pressure responsive means is in another position.

4. A retard device for automatic sprinkler systems comprising a central cylindrical casing section and upper and lower casing sections adapted to be secured to the central section, a diaphragm between the upper and central casing sections spring-pressed toward said central section, a partition within said central section dividing the space therein into inlet and accumulation chambers and provided with two passages therethrough, a second partition in said central section forming an outlet chamber therein communicating with said inlet chamber, means for connecting a water supply pipe to said inlet chamber and a water outlet pipe to said outlet chamber, a valve controlling the communication between said inlet and outlet chambers adapted to operate by movement of the diaphragm between the central and upper casing sections, a diaphragm between the lower and central casing sections spring-pressed toward the central casing and having a drainage passage therethrough adapted to be closed only when the inlet chamber is under pressure, and means for closing one of said passages in said first mentioned partition when the pressure of the inlet cham-

ber exceeds that of the accumulation chamber.

5. A retard device comprising a central cylindrical casing section and upper and lower casing sections adapted to be secured to the central section, diaphragms between adjacent casing sections biased toward said central section, a partition within said central section dividing the space therein into inlet and accumulation chambers and provided with two passages therethrough, a second partition in said central section forming an outlet chamber therein communicating with said inlet chamber, means for connecting a water supply pipe to said inlet chamber and a water outlet pipe to said outlet chamber, a valve controlling the communication between said inlet and outlet chambers adapted to be operated by movement of the diaphragm between the central and upper casing sections, and means for closing one of said passages in said first mentioned partition under certain pressure conditions in said inlet chamber.
- 10 6. A retard device according to claim 5 including electrical contacts carried by said upper casing section and means operable by the diaphragm between the central and upper casing sections for closing said contacts when
- 15 30 said diaphragm operates to establish communication between said inlet and outlet chambers.

7. In a retard device according to claim 5 means operable by gravity under certain pressure conditions in said inlet chamber for establishing communication between said inlet and outlet chambers independently of the diaphragm between the upper and central casing sections.

- 40 40 In testimony whereof, I have signed my name to this specification.
